UNITED STATES PATENT OFFICE.

THEODORE SHAVER, OF IRETON, IOWA; ELIZABETH SHAVER ADMINISTRATRIX OF
SAID THEODORE SHAVER, DECEASED.

TANK-HEATER.

1,154,065.

Specification of Letters Patent.

Patented Sept. 21, 1915.

Application filed December 31, 1914. Serial No. 879,929.

To all whom it may concern:

Be it known that I, THEODORE SHAVER, a citizen of the United States, residing at Ireton, in the county of Sioux and State of Iowa, have invented certain new and useful Improvements in Tank-Heaters, of which the following is a specification.

This invention relates to certain improvements in tank heaters, and the objects and nature of the invention will be readily understood by those skilled in the art in the light of the following explanation of the accompanying drawings illustrating what I now believe to be the preferred embodiments from among other formations, arrangements and constructions within the spirit and scope of the invention.

An object of the invention is to provide improved means for preventing the freezing of water in stock watering tanks.

A further object of the invention is to provide a tank heater for immersion in watering tanks which will heat the water by means of circulating currents of warm water.

A further object of the invention is to provide a tank heater of few parts and simple construction giving efficient results with the smallest care and attention.

A further object of the invention is to provide a tank heater embodying heat retaining means constructed and arranged to store up heat during the normal operation of the heat generator of the heater, and to slowly give off heat for a considerable length of time to prevent freezing of the water in the stock tank, should said generator become accidentally extinguished.

This invention consists in certain novel features in construction and in combinations and arrangements as more fully and particularly set forth and specified hereinafter.

Referring to the accompanying drawings: Figure 1, is a perspective view of a tank heater embodying my invention, a portion of the top wall thereof being broken away, certain other parts being indicated by dotted lines. Fig. 2, is a longitudinal vertical section. Fig. 3, is a longitudinal vertical section of a modified construction. Fig. 4, is a top plan of the modification illustrated by Fig. 3, with the top wall and parts carried thereby removed.

The tank heater of my invention embodies a box or casing adapted to be submerged

in the body of water to be heated, and having an elevated air inlet through which air is supplied to the interior of the box to support combustion, and having an elevated discharge for the products of combustion from the interior of said box. A water heating pipe or conduit extends longitudinally through the interior of this box and the ends of this conduit or pipe are open at the exterior of the box and in the body of water to be heated. Any suitable burner, or other heating device, is arranged within the box, to heat said pipe or conduit and the water therein and thereby cause the water to constantly flow in one direction through said pipe and consequently set up a circulation in said body of water sufficient to prevent freezing thereof.

In the particular example illustrated, I show a suitable water tight metal (or other suitable material) box *k*, having its otherwise open top closed by a removable top wall or cover *l*, secured to the box in any suitable manner to provide a water tight joint between the cover and top edges of the box walls. This can be accomplished by suitable interposed packing *m*, and stove or other suitable bolts *M*, for clamping the cover to the box walls and against the intervening packing. This box is intended to be placed in a stock water tank and to be of sufficient weight to maintain its position resting on the floor of such tank, yet the box is as small as possible in size to take up a minimum amount of space in the tank and so that the box will be completely submerged with its cover *l*, below the water level in the tank. I show the box formed with bottom feet or supports *p*, to rest on the floor of the tank and thereby hold the bottom wall of the box a distance above the floor of the tank, although my invention is not so limited.

The means I provide for setting up a circulation of water in the tank comprise a suitable heater within said box and a water conduit extending through said box and exposed therein to the heat generated by said heater. This water conduit consists of a pipe extending longitudinally throughout the length of the box and projecting through and beyond the end walls of the box and forming water tight joints with said end walls. The projecting ends *a*, *a'*, of this pipe are submerged in the water in the tank and are open for the free flow of water into

and from the pipe, while the portion a' , of the pipe within the box is imperforate and forms opposite lateral loops or offsets so that the portion a' , of the pipe is in the form of a flat coil to maintain a maximum surface area of pipe within the box subject to the heat of the burner as well as a maximum volume of water likewise subject to said heat. This pipe is longitudinally inclined 5 throughout the length of the box from the pipe inlet end a , upwardly toward the pipe outlet or discharge end a^2 , to maintain a constant flow of water through said pipe and from the elevated discharge end a^2 , 10 thereof for the purpose of drawing water into the inlet end a , thereof and consequently setting up a circulation of water within the stock tank. The heating or circulating coil is arranged to constantly discharge a stream of warm or heated water into one portion of the body of water in the tank while constantly drawing in cold or cool water from the lower part of a different portion of the body of water within the 15 tank. The body of water within the tank will hence be kept circulating while the temperature thereof will be maintained at a sufficiently high degree to prevent freezing. As before stated, any suitable means can be 20 provided within the box to heat said water circulating pipe and also to heat the walls of the box and thereby aid in raising the temperature of the water in the tank and avoid waste of heat so far as possible. In 25 the particular example illustrated, I show a suitable oil (or other liquid fuel) burner h , arranged just above the floor or bottom wall of the box and immediately below the lower or inlet end of the coil a' , within the box. 30 This burner is supplied with fuel through a supply pipe j , extending through the bottom wall of the box and forming a watertight joint therewith. This pipe extends exteriorly of the box to any suitable liquid 35 fuel supply tank g , the flow of liquid from which can be controlled by a valve S . The supply tank is supported in an elevated position above the water in the stock tank and is carried by the box, any suitable means being provided for this purpose. 40

To maintain the necessary flow of air into the box to support combustion, I provide a down-draft air tube e , having its inlet end elevated above the level of the water in the 45 stock tank while the lower outlet end of said tube is arranged directly and approximately centrally above the burner h , and comparatively close thereto so that the down draft or blast of air will spread the burner flame, 50 for obvious purposes and resulting advantages. This air tube is vertical and the interior thereof is unobstructed, although I preferably provide a valve or damper e' for the inlet end thereof to control the inflow 55 of air for obvious purposes. This air tube

depends a considerable distance into the interior of the box and rises a considerable distance above the cover or top wall of the box and any suitable means or arrangement can be provided for supporting said tube, 70 although I show the tube supported by its upper end where the tube is fixed to and opens through a cap or closure f' , removably fitted on and closing the otherwise open upper end of a vertical watertight casing 75 forming well f , rising from and fixed to the top wall or cover of the box and opening therethrough into the combustion chamber d , or interior of the box. This well rises to an elevation above the water level in the 80 tank and is of considerably greater diameter than the air tube so as to provide an air space around said tube in open communication to the combustion chamber in the box. After the box has been submerged in the 85 water in the stock tank, and the burner has been supplied with fuel, the fuel on or in the burner can be ignited by a suitable flaming torch applied to the burner through the well f , after the cap f' , carrying the air tube, 90 has been lifted from the well. After the burner has been ignited, the air tube is inserted in the well and the cap f' , is placed on the well to tightly close the same. 95

To maintain the draft longitudinally of the box and along the circulating pipe coil, I provide a discharge pipe c , from the upper portion of the end of the box opposite the end in which the burner is located, and this pipe is extended vertically to a point above 100 the water level in the stock tank. The cover or top wall l , of the box is preferably arranged at an inclination longitudinally of the box and upwardly toward the discharge pipe c , to promote the passage of hot products longitudinally of the box and to the discharge pipe and thereby aid in maintaining the draft through the box necessary to support combustion. 105

If so desired, a partition can be arranged in the box to form a vertically-disposed fire or combustion chamber at one end and extending to the floor of the box and containing the heat generator, and an upwardly inclined deflector below the circulating pipe 110 and extending longitudinally of the box from the upper portion of said chamber to the discharge end of the box. The inclined position of said partition cooperates with the top wall or cover l , in forming an upwardly inclined flue or passage extending longitudinally of the box from the combustion chamber to the discharge pipe c . The water circulating pipe a' extends transversely 115 across said combustion chamber and directly above the heat generator to receive the full force and effect of the flame thereof, and said pipe also extends throughout the length of said flue wherein the hot products from the generator are concentrated and confined 120

to travel throughout the greater portion of the length of said pipe after leaving the combustion chamber, to reduce waste of heat to the minimum. It will be observed that a 5 most extensive surface area of the circulating pipe is directly exposed in the box to the heating effect of the burner flame and the resulting hot products. In the example illustrated, by Figs. 1 and 2, this partition is 10 composed of a metal sheet bent approximately at right angles and inserted in the box to form the vertical wall o , and the upper longitudinal inclined wall o' . The lower edge of the vertical wall rests on the floor of 15 the box near the burner and extends upwardly a suitable distance to form the right hand (Fig. 2) vertical wall of the combustion chamber while the remainder of the partition extends from the upper end of 20 said vertical wall o , to the end wall of the box just below the discharge pipe. This partition is preferably imperforate and occupies the full width of the box and is preferably secured at its edges to the inner surfaces 25 of the box preferably to form air tight joints. The partition in connection with the walls of the box thus forms a closed air space or chamber b , within the box beside the combustion chamber and below the flue 30 therefrom. This chamber or dead air space performs a peculiar function in that it serves to store and retain heat conducted thereto through the walls thereof formed by the partition. The air in said space becomes 35 gradually or slowly heated during the operation of the heater and the heat is thereby stored therein to be utilized in case of emergency in greatly delaying the cooling of the water in the stock tank to the freezing 40 point. If the burner should become accidentally extinguished through lack of fuel or from any other cause, during freezing weather, the heat stored in chamber b , will be gradually transferred by conduction from 45 the dead air in said chamber to the water in the stock tank, and will keep the water above freezing temperature for quite awhile, several hours, in fact, under certain conditions. The purpose of the heat retaining space is 50 to keep the water from freezing, in the emergency mentioned, until the fact that the heater is not properly operating, has been observed by some one.

Where the partition is composed of sheet 55 metal, or where the box is composed of sheet metal, the walls of the chamber b , are preferably imperforate and the chamber air tight, inasmuch as the sheet metal walls will expand and contract by bulging or otherwise to accommodate the variation in pressure due to the expansion and contraction of the air in the chamber. Where the tank box and the partition are composed of cast iron or the like, it is usually necessary to provide 60 one or more vent holes in the partition for

the escape of air from the chamber b , to relieve the pressure therein when the air becomes highly heated.

In Fig. 3, I show a tank box construction particularly designed for use where the box is composed of cast iron or the like. In this construction, I, in effect, omit the top wall or length o' of the partition of Figs. 1 and 2, and provide several spaced parallel vertical partitions o^2 , o^3 rising from the floor of the box between the burner and the rear end of the box with their horizontal top edges terminating short distances below the circulating pipe, thereby forming air spaces, chambers or pockets b' , b'' . The partitions o^2 , o^3 will deflect the hot products from the burner flame upwardly and cause the same to travel along the water circulating pipe; will hold the heat thereto, as said products travel toward the discharge pipe c . The air in the pockets b' , b'' , will gradually become heated and heat will thereby be stored and retained in said pockets. If the burner becomes extinguished after operation for a sufficient length of time to highly heat the air in said pockets, heat will be given off therefrom for a considerable period as hereinbefore described in connection with the structure of Figs. 1 and 2. However, I do not wish to limit all features of my invention to the provision of heat storing or retaining means.

It is evident that various changes, modifications, and variations might be resorted to without departing from the spirit and scope of my invention and hence I do not wish to limit myself to the exact disclosures hereof.

What I claim is;—

1. A tank heater comprising a box adapted to be submerged in the water to be heated and forming an internal heating chamber, said box having a down draft air inlet pipe projecting a distance above the box and having an elevated top inlet opening and depending a distance into the box and at its lower end having an air outlet opening, an outlet pipe from said box having an elevated discharge opening, a burner in the box located immediately below said air outlet opening, whereby the burner flame will be spread by the air from said outlet opening, and water circulating means carried by the box and exposed to the heat generated by said burner.

2. A tank heater comprising a water tight box adapted to be submerged in the water to be heated, said box having a well rising therefrom and at its lower end opening thereinto, a closure for the upper end of said well provided with an air inlet tube depending through the well and into the interior of the box, a discharge flue from the box having an elevated discharge opening, a burner in the box, located immediately below the lower

end of said tube to receive the down draft of air therefrom and a water circulating conduit extending through the box with its portion within the box exposed to the heat of the burner, substantially as described.

3. A tank heater comprising a box adapted to be submerged in the water to be heated and provided with a vertical well rising 10 from an opening through the box top, a removable closure for the upper end of said well having an air inlet opening and a depending air tube, said tube being removable with said closure, a burner in the box arranged below said well, a discharge pipe extending from the interior of the box to an elevated point, and a water circulating coiled pipe in the box and opening into the exterior of the box and arranged above and exposed to the heat of said burner, said air tube extending down between the convolutions of said pipe and having its lower discharge end arranged directly above said burner.

- 25 4. A tank heater comprising a box having a water circulating pipe extending longitudinally therethrough, a partition in the box forming an air chamber and heat directing walls below said pipe, a burner in one end portion of the box, and means for maintaining a draft through said box to support combustion.

- 30 5. A tank heater comprising a longitudinally elongated box having a longitudinally inclined removable top, a longitudinally inclined water circulating pipe extending throughout the length of the upper portion of said box with its ends open to the exterior thereof, said pipe within the box

formed with oppositely extending lateral loops, an air supply pipe carried by said top and rising therefrom, an outlet pipe from the rear end of the interior of the box to an elevated point, a burner in the lower portion of the front end of the box below said 45 water circulating pipe and provided with a fuel supply pipe extending to an elevated point at the exterior of the box, and means within the box to the rear of said burner and below the portion of the water circulating pipe to the rear of the vertical-plane of the burner to form the longitudinal flue in which said circulating pipe is arranged, substantially as described.

6. A tank heater comprising a box provided with a heat generator and an air inlet and discharge, said box embodying a heat retaining air space or chamber, and a water circulating conduit in said box and subject to the heat of said generator and arranged 50 above said air space or chamber, substantially as described.

7. A tank heater comprising a box embodying a heat retaining chamber or space within the walls of the box and adjacent to the floor thereof and a combustion chamber to one side of said space and a discharge flue from said combustion chamber and extending over said heat retaining space, and a water circulating conduit extending through 65 said box and arranged across said combustion chamber and in said flue.

In testimony whereof I affix my signature in presence of two witnesses.

THEODORE SHAVER.
